CLAIM

The ornamental design for a calculator, as shown and described.

DESCRIPTION

FIG. 1 is a perspective view showing the front, bottom and right side of the calculator showing my new design.

FIG. 2 is a front view thereof.

FIG. 3 is a right side view thereof.

FIG. 4 is a top view thereof.

FIG. 5 is a back view thereof.

FIG. 6 is a bottom view thereof.

FIG. 7 is a perspective view thereof showing the front, right side and bottom of the calculator of FIG. 1 with the keyboard extended; and,

FIG. 8 is a perspective view thereof showing the back, bottom and left side with the keyboard extended.

The broken lines depict environmental subject matter only and form no part of the claimed design.
